UNITED STATES PATENT OFFICE.

MAUD S. GEORGE, OF ST. LOUIS, MISSOURI.

GARMENT.

1,104,185.

Specification of Letters Patent.

Patented July 21, 1914.

Application filed October 18, 1913. Serial No. 796,038.

To all whom it may concern:

Be it known that I, MAUD S. GEORGE, a citizen of the United States of America, residing at St. Louis, in the State of Missouri, 5 have invented certain new and useful Improvements in Garments, of which the following is a specification.

My invention relates to improvements in undergarments for women and the objects 10 of my improvement are to provide a garment attractive in appearance, comfortable in use, inexpensive in manufacture and which combines in novel fashion an underskirt adjustable to waist, hip and thigh measurement and a separable rubberized cloth 15 portion serving to protect the outer garments from stain during the catamenial period. These desiderata I attain by the combination and arrangement of parts shown in 20 the accompanying drawing, in which—

Figure 1 is a view of the garment as worn and Fig. 2 a plan view of the inside thereof, the sections being laid flat.

Referring to the drawing, in which like 25 numerals refer to like parts throughout the several views, it will be noted that the article comprises a front section 1 and a rear section 2, the upper margin of section 1 being provided with a plurality of loops 3 by 30 which it is adjustably and detachably supported upon a belt 4 to which rear portion 2 is preferably attached by stitching. Secured to each side of each of said sections are tapes 5 (of elastic or other webbing) 35 by means of which, in conjunction with loops 3 sliding upon belt 4, the garment is made adaptable to various waist, hip and thigh measurements and upon the inner surface of section 2 a water-proof catamenial 40 apron 6 is detachably secured by means of snap-hooks or glove-fasteners 7. Obviously, apron 6 can be instantly removed and the balance of the garment simply worn as a short skirt found especially useful in connection with close-fitting dresses of thin 45

material to conceal the limbs of the wearer, or section 1 can be dispensed with by slipping it off belt 4 and the remainder of the garment used during the catamenial period. However, aside from its valuable features 50 of adjustability, whereby one and the same garment can be worn by either a thin or a stout person without the discomfort of gathers at the waist line, the greatest benefit 55 of my invention resides in the fact that, when used complete, there is afforded in one garment complete concealment of the limbs and means for preventing discoloration of the outer clothing.

What I claim as new and desire to secure 60 by Letters Patent is:—

1. An underskirt comprising a belt and separate skirt sections 1 and 2 depending therefrom, one of said sections being permanently secured to said belt, the other 65 thereof having a series of loops disposed along its upper margin through which said belt is projected, whereby one section may be instantly detached from the belt, and tapes secured upon and adapted to detachably connect said sections, substantially as and for the purposes described.

2. An underskirt comprising a belt and separate skirt sections 1 and 2 depending therefrom, a sheet of water-proof material 75 detachably secured to one of said sections, said section being permanently secured to said belt, the other of said sections having a series of loops disposed along its upper margin through which said belt is projected, 80 whereby one section may be instantly detached from the belt, and tapes secured upon and adapted to detachably connect said sections, substantially as and for the purposes described.

MAUD S. GEORGE.
